FURNACE SEAL

Howard M. Andersen, Philadelphia, and Robert E. Buckholdt, Abington, Pa., assignors to Selas Corporation of America, Dresher, Pa., a corporation of Pennsylvania
Filed Nov. 3, 1960, Ser. No. 67,052
4 Claims. (Cl. 263—40)

The present invention relates to furnaces, and more particularly to a seal to be used between a stationary and a movable part of a furnace structure.

In most furnaces there are parts that move relative to each other to give access to the interior of the furnace, and for other reasons. The space between these parts must be sealed to prevent inflow of air or outflow of furnace gases. A good seal is particularly necessary with some types of continuous strip annealing furnaces in which the furnace is moved from a position surrounding the strip to a position adjacent thereto.

It is an object of the invention to provide a seal between a movable and a stationary part of a furnace system.

It is a further, and more specific, object of the invention to provide a mechanically operated seal between the movable furnace portion and the stationary portion of a strip heating furnace structure.

In practicing the invention, the stationary portion of the furnace structure is provided with a heat resistant seal that can be moved from a retracted position away from the movable furnace unit into a sealing position in which it engages a sealing flange on the movable furnace unit.

The various features of novelty which characterize our invention are pointed out with particularity in the claims annexed to and forming a part of this specification. For a better understanding of the invention, however, its advantages and specific objects attained with its use, reference should be had to the accompanying drawings and descriptive matter in which we have illustrated and described a preferred embodiment of the invention.

In the drawings:

FIG. 1 is a perspective view diagrammatically showing the furnace structure,

FIG. 2 is a side view of a portion of the furnace seal, FIG. 3 is section view taken on line 3—3 of FIG. 2, FIG. 4 is a plan view of a corner of the seal, and FIG. 5 is a view of a modified form of seal.

Referring to FIG. 1 of the drawing, there is shown a furnace structure including a furnace unit 1 which may be, and preferably is, of the type shown in Patent 2,869,864, which is used for heating continuously strip material for annealing or other purposes. The furnace unit is mounted for lateral movement between fixed portions including an upper duct section 2 and a lower guide section 3. It will be seen that the strip 4 passes vertically through the sections 1, 2 and 3, and is heated during its passage through furnace unit 1. The furnace, as described in more detail in the above mentioned patent, is U-shaped in section, and is provided with a slot 5 in one edge thereof. In normal operation of the furnace, this slot is closed by engagement of the edge of the furnace with a stationary abutment 6 that extends the length of the furnace unit. The furnace is provided adjacent to its upper end on each side with a pair of rollers 7 that ride on tracks 8 extending transversely of the furnace. The furnace is in the position shown when it is heating the strip, but can be moved to the right in the drawing along the tracks 8 beyond the edge of the strip. When this is done, the strip will pass between the edges of slot 5, so that the furnace can be moved without disturbing the strip. The upper end of the furnace can be sealed by a conventional sand seal arrangement shown at 9. The lower end of the furnace, however, should

2

be sealed with an arrangement which will give a more positive seal than is possible with a sand seal. The invention is concerned primarily with the details of this seal and its combination with the furnace structure.

Referring to FIGS. 2, 3 and 4 of the drawing, it will be seen that around the lower edge of the furnace there is provided an outwardly extending flange 12 against which a movable seal strip presses to close the space between the furnace unit and the stationary guide section 3. The seal strip is comprised of a plurality of asbestos tapes that are placed on edge with alternate wide tapes 13 and narrow tapes 14. These tapes rest upon a ledge that is formed by one flange of an angle iron 15 which is welded to a vertically extending plate 16. The strips are held in position on the flange 15 and are forced against plate 16 by a squeeze plate 17 and bolts 18.

The plate 16 extends entirely around portion 3, and forms a sliding frame so that the parts attached thereto can slide vertically into and out of engagement with flange 12. The guiding means for the frame or plate 16 consists of an angle iron that is fastened to and projects beyond the edge of the lower guide section 3. This angle iron is provided with a horizontal flange 19 and a vertical flange 21, which is separated from frame 16 by a spacer 22.

Each side of frame 16 is resiliently forced toward spacer 22 by spring force. To this end bolts 23 extend through flange 21 and spacer 22 beyond frame 16. Each of these bolts has on it a pair of washers 24 against the inner surfaces of which the ends of a compression spring 25 bear. The force of these springs, and therefore the force with which the sides of frame 16 are moved toward flange 21, can be adjusted by nuts 26 which are received on bolts 23. A series of these bolts and the parts carried thereby extend at spaced distances along the flange 21 and around stationary portion 3. Vertical movement of frame 16 relative to spacer 22 is limited by means of slots 27 formed in the frame, and which surround the bolts 23. It is noted that washers 24 are large enough to engage and push against the frame around the sides of the slot. It is also noted that the vertical flange of angle iron 15 is provided with cut-out portions 28 around the washers 24, so that these flanges will not interfere with vertical movement of the seal.

In order to prevent any leakage between frame 16, which carries the seal members 13 and spacer 22, there is provided a washer 29 of asbestos tape or the like, which rests on spacer 22 between the vertical leg 21 of the angle iron and the frame. This washer is held in position by a clamp 31 that is bolted to the horizontal leg 19 of the angle iron.

The frame 16 and the parts carried thereby are moved vertically into and out of engagement with the flange 12 to seal the space between the furnace unit 1 and the stationary portion 3. This is accomplished by having frame 16 moved vertically through hydraulic or pneumatic pressure that is applied at opposite ends of cylinders 33 attached by brackets 34 to the stationary portion 3. Each of these cylinders receives a piston that is attached to the end of a piston rod 35. The piston rods are connected by links 36 with the flange 15. To this end the upper end of each link 36 receives a pivot pin 37 that extends through a yoke 38 formed by lugs that are welded to flange 15.

In the operation of the apparatus, when strip is being heated, the furnace unit 1 is in the position shown in FIG. 1 between the stationary duct portion 2 and lower portion 3 of the furnace structure. At this time, fluid pressure is applied to the lower end of the cylinders 33 to move the seal 13 tightly into engagement with the bottom surface of flange 12. Thus the space between the furnace unit 1 and the structure 3 is sealed against the inflow of air into the furnace. The tapes 13 are sufficiently resilient to take

care of any slight irregularities in the lower surface of flange 12. The continuous washer 29 will prevent leakage past the frame 16. When the furnace is to be retracted to the right in FIG. 1, in order to stop heating of the strip, fluid pressure is applied to the upper ends of the cylinders 33 to move frame 16 and the sealing strips downwardly away from flange 12. The furnace can then be moved to its retracted position. It will be seen from FIG. 3 of the drawing that the space between flange 12 and flange 19 is slightly below the parting line between the center portion of the furnace and the top of portion 3 of the furnace structure. In order to prevent radiation from the furnace from injuring the metal portions of the seal, there is provided a refractory block 39 which is horizontally aligned with the parting line. It will therefore be seen that all metal parts of the seal are protected from direct radiation of the hottest portion of the furnace, so that these parts will not be affected adversely by radiation.

In FIG. 5 there is shown another form that the furnace seal can take. In this figure, the lower end of the furnace unit 1 has running around its edge a water jacket formed by an outwardly extending flange 41 and a channel 42. There is also provided a water jacket 43 around the edge of stationary portion 3 of the furnace. This latter water jacket has a flange 44 extending outwardly from it, which flange does not project outwardly as far as the lower surface of channel 42. The seal extends between flanges 42 and 44 and includes a pair of asbestos ropes 45 and 46 extending around portion 3, that engage respectively the lower surfaces of these flanges. Rope 45 is held in a backing member 47, while rope 46 is held in a backing member 48. These two members are welded along their length to a plate 49, so that the ropes and the plate form a unit. The plate 49 is pivoted at spaced points 51 to supports 52 that are located at spaced points around furnace portion 3. The supports are raised and lowered to move the seal ropes to engagement with their respective flanges by means of a series of rods 53 forming part of diaphragm motors 54 that are mounted on portion 3 by brackets 55. The motors are of the type which are biased by weight of the parts carried by rods 53 in a downwardly direction to open the seal. The application of pressure through pipes 56 to the lower surface of the diaphragm chambers 54 will move the rods 53 upwardly to close the seal.

In this embodiment of the invention, as in the previous one, it is intended that the flanges 42 and 44 extend entirely around the periphery of the furnace. The ropes 45 and 46 also extend around the furnace, so that when the seal is to be closed, the application of air to the diaphragm motor will move the ropes into engagement with the flanges 42 and 44. In view of the fact that plate 49 carrying the seals is pivoted to its supports, this plate can rock slightly to insure that a good seal will be obtained even though there may be slight relative movement between the furnace and stationary portion 3 due to expansion of the furnace as its temperature is changed.

From the above, it will be seen that we have provided a furnace seal which can be used between a stationary and a movable portion of a furnace structure, and one that can be readily opened when it is desired to move the movable portion of the furnace. Since the sealing elements are made of a material that is slightly resilient, the application of pressure to the seal supporting members will close the space between the movable and stationary portions of the furnace structure tightly, even though these portions may shift a small amount relative to each other.

While the above description shows that the seal itself is carried by a stationary portion of the furnace structure, and this is the desirable arrangement, it will be obvious that the seal could be on the movable portion of the furnace if it was desired. In either case, the operation and the sealing would be the same.

While in accordance with the provisions of the statutes, we have illustrated and described the best form of embodiment of our invention now known to us, it will be apparent to those skilled in the art that changes may be made in the form of the apparatus disclosed without departing from the spirit and scope of the invention set forth in the appended claims, and that in some cases certain features of our invention may be used to advantage without a corresponding use of other features.

What is claimed is:

1. In a furnace structure, a furnace having an opening therein and a first flange extending outwardly from said furnace substantially perpendicularly to said opening, structure spaced from said furnace and disposed in front of said opening, and means to seal the space between said furnace and structure around said opening comprising a second flange surrounding said structure, a frame substantially the same size as said first flange surrounding and slidable on and guided by said second flange, sealing means between said second flange and frame, means to force said frame toward said second flange to compress said sealing means, a sealing strip attached to said frame and extending toward said first flange, and means to move said frame toward and from said first flange to move said sealing strip into engagement with said first flange and thereby seal the space between said furnace and structure.
2. In combination, a furnace having an opening therein, a flange on said furnace around said opening and extending substantially perpendicularly thereto, structure located in front of said opening and spaced from said furnace, means on said structure having a guiding surface aligned with said flange and perpendicular thereto, a frame surrounding and slidable on and guided by said surface, sealing means operative to prevent gas leakage between said frame and surface, means to force said frame toward said surface against said sealing means, a sealing strip on said frame and projecting toward said flange, means to hold said sealing strip rigidly on said frame, and means to slide said frame in opposite directions on said surface to bring said sealing strip into and out of engagement with said flange.
3. The combination of claim 2 including means to mount one of said furnace and structure for movement laterally of the other.
4. The combination of claim 2 including cooperating means on said furnace and structure to shield said sealing strip from direct radiation from said furnace.
